Attorney

UNITED STATES PATENT OFFICE.

HENRY E. JOHNSON, OF OMAHA, NEBRASKA.

PLATFORM-FRAME FOR HAND-TRUCKS.

1,099,924.

Specification of Letters Patent. Patented June 16, 1914.

Application filed October 7, 1912, Serial No. 724,272. Renewed February 27, 1914. Serial No. 821,570.

To all whom it may concern:

Be it known that I, HENRY E. JOHNSON, a citizen of the United States, residing at Omaha, in the county of Douglas and State 5 of Nebraska, have invented certain new and useful Improvements in Platform-Frames for Hand-Trucks, of which the following is a specification.

This invention relates to an improvement 10 in the frames of hand trucks, and has for its object to provide a platform frame of few and simple parts so that the construction may be stronger, more durable, and less expensive than ordinary.

15 The invention includes metallic corner pieces, each formed as a longitudinally-apertured segment with wings and a reinforcing cap, the apertures of the segments providing sockets or holders for the stakes 20 or handles of the truck, the wings providing mountings for the ends of the side and end-plates of the frame, the advantages being that convenience, simplicity and economy in manufacture is attained since integral blocks 25 or castings, uniform in size and structure, are used for all of the corners of the platform, and a mounting is provided in the plane of the platform for the handles or stakes, instead of the ordinary outside yokes 30 or brackets.

The invention has reference to the segmental form of the corner pieces with upset curved flanges, to the ridges, channels and recesses of the wings, and to the raised 35 panels, channels and recesses formed in the side and end plates, all arranged to register with each other and with the ends of the cross strips or boards which form the upper face of the platform.

40 The invention consists of the novel construction, combination and arrangement of parts as described herein and claimed, and as illustrated in the drawing, wherein,—

Figure 1 is a perspective view of the reinforcing cap used for each of the corners of the platform. Fig. 2 is a perspective view of a casting employed. Fig. 3 is a perspective view showing a part of a side plate or end plate of the frame. Fig. 4 shows two 50 end portions of a hand truck in side elevation, parts being broken away to show construction. Fig. 5 is a detail showing a plan view of a handle. Fig. 6 is a broken plan view of the platform, on a reduced scale, the 55 standards being removed.

Referring now to the drawing for a more

particular description, numeral 6 indicates a corner piece or casting consisting of a segmentally formed part 7 having a flat, upper surface or end *a*, and a curved ridge or flange *b* projecting above and at the outer part of said end, and formed midway between its flat upright sides *c* with a longitudinal aperture 8 opening flush with the inner wall of the ridge, said segmental part 7 having, integral therewith and at the inner part of its sides *c* the pair of wings 9, said wings being rectangular in cross-section and disposed in angular relation with reference to each other, and preferably having a uniform length, width and thickness, each wing being transversely apertured as indicated at *t* and formed, upon its outer side, parallel with the adjacent side *c* of part 7, with a lug or ridge *d*; the upper faces *e* of the wings being flat and disposed in the plane of the upper end *a* of said part 7. As thus described, channels *f* are formed between ridges or lugs *d* and sides *c* of the segmental part 7, and a recess *g* is formed outwardly 80 of each ridge or lug *d*.

At 11 is indicated one of the end plates for the platform, and at 11' are indicated side plates therefor. They are preferably constructed as straight wooden bars or strips, and each of said plates is formed with a longitudinal recess *h* opening upon its upper face and inner side to provide a ridge *i* at its outer side and a flat bearing-face *k*; and each of said plates is chamfered near its end to form a transverse groove *m* opening upon its lower side and upon the bearing-face *k*; and a raised panel *n* between groove *m* and the adjacent terminal of said plate; and at *o* is indicated a recess or groove disposed parallel with and adjacent to groove *m*. Apertures *p* are formed in the plates and they extend through panels *n*.

To assemble the parts to form a platform, each side plate and end plate is disposed with one of its panels *n* seated in one of channels *f* of a corner piece, the end of each plate bearing against a side *c*, the ridge *d* engaging within a groove *m*, the end of wing 9 being disposed in a groove *o*, apertures *t* and *p* being in alinement; and at this time the bearing-face *k* of each plate will be flush with faces *e* of the wings.

At 12 is indicated a curved, metallic reinforcing cap provided with apertures *r*, the degree of curvature corresponding to the curvature of the segments 7. One of these

caps is provided for each corner piece, and when the plates 11, 11' and the corner pieces have been arranged as described, the caps 12 may be secured upon the outside to cover 5 the curved parts of members 7 and also covering a part of the outer sides of plates 11 and 11', bolts or keepers *s* being employed to traverse apertures *t*, *p* and *r* for securing these parts in rigid relation. By the construction as described, it will be noted that 10 the end portions of plates 11 and 11' are supported between the wings 9 and caps 12, the walls of the recesses and grooves providing adequate holding means when engaged 15 by the panels and ridges; and since there is uniformity of structure for the plates as compared with each other, and uniformity in the construction of the corner pieces, manufacture is less expensive and more convenient 20 than ordinary.

At 10 are indicated upright standards, preferably constructed of metallic tubes or pipe; they operate as stakes and as supports for the transverse handles *u*, said handles 25 being connected with the standards by couplings *v*.

At *w* are indicated the wood cross-strips which form the upper surface of the platform and it will be noted that they may be 30 disposed upon the flat surfaces *a* and *e* of the corner piece and upon the bearing faces *k* of recesses *h* of the plates 11 and 11'.

It is considered that the platform for the hand truck as described provides a much 35 lighter construction than ordinary, since wood material may be employed for all of its parts except the caps and corner pieces.

One of the particular advantages of the 40 construction as shown relates to the mounting for standards 10, this mounting being at the middle, substantially, of the metallic corner pieces. As is well known, in the use of hand-trucks, stresses and strains are directed outwardly of the platform. It will 45 be seen that the upwardly-projecting ridges *b* operate as braces for the standards, since the apertures 8, which provide holders or sockets for their lower ends, open upon the upper surface or end *a* of the corner pieces 50 flush with the inner wall of said ridges, and

the mounting for the standards provide bearings to resist outward stresses equal to the length of apertures 8 plus the height of said ridges, and since this mounting is in the plane of the platform, the standards are 55 not obtrusive, as they certainly would be if mounted upon the outer face of the platform.

It will be noted that the platform frame provides a strong construction at the corners where most needed, the outer surface of 60 the end and side plates being disposed substantially flush with the curved part of the segments, the reinforcing caps bearing adjacent to and outwardly of the plates and upon the segments. 65

Having fully described the several parts and their uses, a further explanation relating to operation is not necessary.

What I claim and desire to secure by Letters Patent is,—

A platform frame for hand trucks, comprising side and end plates and connecting corner irons, each of said corner irons comprising a body portion and projecting wings disposed at right angles to each other, said wings extending in parallelism with and overlapping said side and end plates, interengaging, vertically disposed ribs and grooves formed in said plates, and said wings to resist endwise separation thereof, 75 fastenings traversing said wings and plates, an upstanding rib formed longitudinally upon the upper face of said side and end plates, a curved rib formed upon the upper face of each corner iron and having its terminals alined with the ribs of the side and end plates whereby a ledge is formed, lying 80 inside of said ribs, said corner irons having vertical standard receiving openings formed therein, opening at the top of said ledge and 85 one portion of the wall of said opening alining vertically with the inner face of said curved rib. 90

In testimony whereof I have affixed my signature in presence of two witnesses.

HENRY E. JOHNSON.
